UNITED STATES PATENT OFFICE.

HERBERT G. LA SOR, OF LOS ANGELES, CALIFORNIA.

INKING-ROLLER TRUCK.

Application filed December 11, 1922. Serial No. 606,227.

To all whom it may concern:

Be it known that I, HERBERT G. LA SOR, a citizen of the United States, residing at Los Angeles, in the county of Los Angeles 5 and State of California, have invented a new and useful Inking-Roller Truck, of which the following is a specification.

This invention relates to an inking-roller truck, such as used in printing presses for 10 inking the faces of the type set up in a form. In the operation of such inking rollers, they are guided over the type by means of guide-rollers, which run on guides, or guide-rails located at each side of the 15 form. The diameter of the inking roller is subject to variation for different reasons and under some circumstances the roller may pass too close to the type or too far from the face of the type, thereby producing imperfect 20 type impressions on the printed sheet.

The general object of the present invention is to produce simple means for overcoming this difficulty and to provide a simple 25 construction of inking roller truck, which will enable the position of the inking roller to be slightly altered at will, to the end that it will operate effectively in the inking process; also to provide means whereby 30 the alinement of the roller, as suggested, can be accomplished in such a way that after the adaptation or new alinement of the roller has been effected, it will be held positively in a predetermined relation, with 35 respect to the face of the type, that is to say, I avoid the dependence upon a gradually adjusted part and produce a predetermined adjustment, by merely reversing the roller on its shaft.

40 Further objects of the invention will appear hereinafter.

The invention consists in the novel parts and combination of parts to be described hereinafter, all of which contribute to produce 45 an efficient inking roller truck.

A preferred embodiment of the invention is described in the following specification, while the broad scope of the invention is pointed out in the appended claims.

50 In the drawing:

Fig. 1 is a front elevation, showing a portion of an inking roller and indicating the guide rail and a portion of the type supposed to be set up in the form; and also 55 showing the adjacent guide roller, which supports the inking roller.

Fig. 2 is a view similar to Fig. 1, but showing the guide roller in a reversed position, so as to effect an alteration in the alinement of the inking roller with respect to 60 the type faces.

Fig. 3 is an end elevation of the roller and shaft.

Fig. 4 is a cross section taken on the line 4-4 of Fig. 2.

Fig. 5 is a cross section taken on the line 5-5 of Figure 3.

Referring more particularly to the parts, 1 represents the inking roller which may be 70 constructed in the usual way and mounted on a shaft 2, said shaft carrying a roller at each end such as the roller 3. These rollers roll along on a pair of oppositely disposed guides or guide rails 4, fixed at each side of the printing press, in such a way that when 75 the inking truck passes over the faces of the type A, set up in a type form, the ink will be transferred from the roller to the faces of the type.

With such a construction, a very slight 80 variation in the diameter of the inking roller 1, or the guide roller 3, may produce imperfect transference of the ink to the type. It has been attempted to overcome this difficulty by providing for an adjustment of the 85 diameter of the guide roller, and this method involves a gradual increase or decrease in the diameter of the guide roller, the result of which is that constant readjusting is necessary. It also frequently happens that a 90 printing job may involve the use of a number of inking rules, set up in the form, which have a tendency to cut or score the face of the inking roller. Under such circumstances my invention enables the inking roller to be 95 raised slightly and alined in a slightly removed position; the amount of removal will be a predetermined amount, which is constant for the press.

According to my invention, I construct 100 the guide roller 3 with two roller parts, 3^a and 3^b, which are preferably made of two distinct pieces, one being of slightly larger diameter than the other. This roller 3 is secured to the shaft 2, which projects over 105 or adjacent to the guide rail 4, by means that will enable the roller to be secured to the shaft 2 in one position, in which the roller part 3^a will roll on the face of the guide rail, and in a reversed position in 110 which the roller part 3^b will roll on the rail.

In order to accomplish this, the roller 3

is preferably composed of a metallic hub 5 (see Fig. 2) which has a bore 6 of suitable diameter to enable it to fit nicely over the end of the shaft 2, and this hub is provided with a keyway or key slot 7 which is not tapered, but which extends at a uniform depth from one end of the hub to the other. The shaft 2 is provided with suitable means such as a pin 8 fixed in the shaft, operating as a stop to limit the inward movement of the roller when it is slid into place. The shaft is also provided with an integral dog or key 9, which may be produced by swaging the side of the shaft 2. This key is of the proper width to fit neatly in the key-way 7, thereby insuring that when the roller 3 rotates, it will impart its rotary movement to the inking roller 1. These parts are also of such relation to each other, that when one of the roller parts is rolling on the guide rail, the other roller parts will be held out of contact with the rail, that is to say, in such a way that it cannot interfere with the operation of the roller part that is bearing on the guide rail. In order to accomplish this, I prefer to provide the roller parts 3^a and 3^b with two rims, 10 and 11, which are constructed of a relatively hard but compressible material, such as fiber, and these two rims are held clamped together; their adjacent faces are preferably cut away by means of an annular groove 12, which is so located that in either position of the roller 3, the groove or gap 12 will come over the outer side face or edge 13 of the rail. This insures that only one of the roller parts can engage the guide rail at a time.

The metallic hub 5 has an integral collar 15 at one side, which is countersunk in the outer face of one of the rims, for example, the rim 11, and the other end of the hub is provided with a screw thread connection 16 to receive a clamping collar or washer 17, which screws into place and which is countersunk into the outer face of the other rim 10.

In order to prevent the rims 10 and 11 from working loose, after they have been tightly clamped, I provide the edges of the collar 15 and the clamping collar 17 with recesses or sockets 18, which enable spanner wrenches to be applied in clamping the rims; and on account of the slightly compressible nature of the fiber of which the rims are composed, the compression in the fiber tends to produce a slight hump, or protruding of the material into the sockets 18; this operates to prevent the unscrewing of the thread connection. In this way I attain the effect of a locknut without necessitating the use of one, and this is very desirable because the construction of the parts at this point necessitates compactness, in order to insure that the parts in operation will clear each other in their movements; for example,

for the sake of clearance, it is advisable to provide the outer edges of the collars 15 and 17 with a slightly beveled face 19.

It will be evident that the use of my invention will enable the alinement of the inking roller 1 to be changed at will. Fig. 1 shows the roller part 3^a of larger diameter, supporting the inking roller on the guide rail 4 and this of course holds the face of the roller further from the face of the type than it would be held if the roller is held in a reversed position as indicated in Fig. 2. In this way I accomplish the necessary alteration of alinement of the roller.

It is understood that the embodiment of the invention described herein is only one of the many embodiments this invention may take and I do not wish to be limited in the practice of my invention nor in my claims to the particular embodiment set forth.

What I claim is:—

1. In an inking roller truck for inking type, the combination of a track rail for guiding the truck over the type, an inking roller having its shaft disposed adjacent to the rail, a guide roller mounted on the shaft having two roller parts, one of said parts being of slightly larger diameter than the other, and means for supporting the roller on the shaft constructed so as to enable the roller to be applied in one position with one of the said roller parts in contact with the rail and in a reverse position with the other roller part engaging the rail, said roller having a gap between the bearing faces of the roller parts whereby when one of the roller parts is resting on the rail the other roller part is held displaced from the rail and out of contact with the same.

2. In an inking-roller truck for inking type, the combination of a track rail for guiding the truck, an inking-roller having its shaft disposed adjacent to the rail, a guide roller having a metallic hub mounted on the shaft and having two rims of a relatively hard and slightly compressible material mounted on the hub, means for clamping the rims on the hub, said hub and shaft co-operating to enable the guide roller to be applied in one position with one of the rims rolling on the rail and in a reverse position with the other rim rolling on the rail.

3. In an inking roller truck for inking type, the combination of a track rail for guiding the truck, an inking-roller having its shaft disposed adjacent to the rail, a guide roller having a metallic hub mounted on the shaft and having two rims of a relatively hard and slightly compressible material mounted on the hub, means for clamping the rims on the hub, said hub and shaft cooperating to enable the guide roller to be applied in one position with one of the

5 rims rolling on the rail and in a reverse position with the other rim rolling on the rail, said rims having a circumferential groove formed at their adjacent faces to produce a gap between the bearing faces of the rims whereby when one of the rims is resting on the rail the other rim is held away from the rail and out of contact with the same.

4. In an inking roller truck for inking type, the combination of a track rail for guiding the truck, an inking-roller having its shaft disposed adjacent to the rail, a guide roller having a metallic hub mounted on the shaft and having two rims of a relatively hard and slightly compressible material mounted on the hub, means for clamp-

ing the rims on the hub, said hub and shaft cooperating to enable the guide roller to be applied in one position with one of the rims rolling on the rail and in a reverse position with the other rim rolling on the rail, said clamping means including a clamping collar having a threaded connection with the hub and having recesses formed in the edge thereof, operating when the rims are clamped, to compress the material in the rims, the material of the rim under the recesses operating to prevent the unscrewing of the clamping washer.

Signed at Los Angeles, California, this 4 day of December, 1922.

HERBERT G. LA SOR.
